(57) **CLAIM**

The ornamental design for a part of a caster with a curved surface, as shown and described.

DESCRIPTION

FIG. 1 Front view of the disclosed design.

FIG. 2 Rear view of the disclosed design.

FIG. 3 Left side view of the disclosed design.

FIG. 4 Right side view of the disclosed design.

FIG. 5 Top view of the disclosed design.

FIG. 6 Bottom view of the disclosed design.

FIG. 7 Perspective view 1 of the disclosed design.

FIG. 8 Perspective view 2 of the disclosed design.

FIG. 9 Reference view 1 showing the use state of the disclosed design; and,

FIG. 10 Reference view 2 showing the use state of the disclosed design.
